(57) **CLAIM**

I claim a vacuum tube amplifier, as shown and described.

DESCRIPTION

FIG. 1 is a front view of the vacuum tube amplifier showing my new design;

FIG. 2 is a top view thereof;

FIG. 3 is a rear view thereof;

FIG. 4 is a bottom view thereof;

FIG. 5 is a side view thereof;

FIG. 6 is an opposite side view thereof;

FIG. 7 is a front perspective view thereof;

FIG. 8 is a rear perspective view thereof; and,

FIG. 9 is an exploded perspective view thereof.

The broken lines represent the portions of the design that form no part of the claim.
